UNITED STATES PATENT OFFICE

138,737

DESIGN FOR A TOOL FOR SEPARATING TELESCOPED MEMBERS OR THE LIKE

Clifford L. Cope, Toledo, Ohio, assignor to The
A P Parts Corporation, Toledo, Ohio, a corpo-
ration of Ohio

Application June 8, 1944, Serial No. 113,907

Term of patent 14 years

(Cl. D54—13)

To all whom it may concern:

Be it known that I, Clifford L. Cope, a citizen
of the United States, residing at Toledo, county
of Lucas, and State of Ohio, have invented a
new, original, and ornamental Design for Tool
for Separating Telescoped Members or the like,
of which the following is a specification, refer-
ence being had to the accompanying drawing,
forming part thereof.

In the drawing,

Figure 1 is a plan view of the tool for separating
telescoped members showing my new design;

Figure 2 is a side elevational view of the tool
shown in Figure 1;

Figure 3 is an end view of the tool.

My design of tool is characterized by the in-
clusion of dual cutting configurations arranged
substantially at right angles to each other.

I claim:

The ornamental design for a tool for separating
telescoped members or the like, substantially as
shown and described.

CLIFFORD L. COPE.
